(57) **CLAIM**

The ornamental design for an edgelit linear highbay light fixture, as shown and described.

DESCRIPTION

FIG. 1 is a top perspective view of a first embodiment of an edgelit linear highbay light fixture

FIG. 2 is a bottom perspective view of the first embodiment thereof;

FIG. 3 is a front elevational view of the first embodiment thereof;

FIG. 4 is a rear elevational view of the first embodiment thereof;

FIG. 5 is a right side elevational view of the first embodiment thereof;

FIG. 6 is a left side elevational view of the first embodiment thereof;

FIG. 7 is a top plan view of the first embodiment thereof;

FIG. 8 is a bottom plan view of the first embodiment thereof;

FIG. 9 is a top perspective view of a second embodiment of an edgelit linear highbay light fixture

FIG. 10 is a bottom perspective view of the second embodiment thereof;

FIG. 11 is a front elevational view of the second embodiment thereof;

FIG. 12 is a rear elevational view of the second embodiment thereof;

FIG. 13 is a right side elevational view of the second embodiment thereof;

FIG. 14 is a left side elevational view of the second embodiment thereof;

FIG. 15 is a top plan view of the second embodiment thereof; and,

(Continued)

FIG. 16 is a bottom plan view of the second embodiment thereof.

The broken lines shown in the drawings are included for the purpose of illustrating unclaimed portions of the edgelit linear highbay light fixture and form no part of the claimed design. The embodiments of FIGS. 1-8 are shown with a symbolic break in the length of the design. The appearance of any portion of the article between the break lines forms no part of the claimed design.

FIG. 9 is the same as FIG. 1 with the symbolic break in the length of the design removed. The remaining views of the second embodiment are the same as FIGS. 2-8 with the symbolic break in the length of the design removed.
